COMBINED WIRE AND RIBBON GRINDER

Louis Illmer, Cortland, N. Y.

Application June 25, 1947, Serial No. 756,843

15 Claims. (Cl. 51—71)

1

This invention relates to a heavy duty surface grinding machine in which a series of abrasive tapes or the like cutting agency is effectively utilized to treat a long reelable work piece of alloy steel or other hard high tensile strand stock when dragged in a closed circuit. A laterally pliable wire or ribbon batch of this kind is herein unidirectionally dragged in successive passes between mated winch drum units at a relatively high velocity to impart an intensified cutting rate to the treated product when brought into operative engagement with a plurality of slowly fed abrasive tapes as carried by either rotating or stationary grinder head units arranged to abrade the entire strand perimeter.

The object of my improvements is to devise a compact strand layout of the indicated character capable of repeatedly reeling a long endless batch of heavy wire or ribbon stock in passes through one or more grinder heads whereby to complete its penetrative abrasive treatment at a fast low-cost production rate and which installation requires a comparatively short intervening shut down period during which to replenish a completely ground batch. Embodied herein are also certain reel structural aspects designed to promote the end in view, preferably when contrived for wires of one-eighth inch or less in diameter.

Reference is had to the accompanying four sheets of drawings of a preferred exemplification, and in which drawings:

Fig. 1 illustrates an elevational side view of my machine provided with pairs of grinder heads, and Fig. 2 represents a top view thereof.

Fig. 3 shows a roller detail taken along 3—3 of Fig. 1, and Fig. 4 is a cross-sectional view of Fig. 1, and Fig. 4 is a cross-sectional view taken along 4—4 of Fig. 3.

Figs. 5A and 5B are taken along 5—5 of Fig. 4 and respectively reveal ribbon and wire stock as alternatively disposed in the same shape of winch groove.

Fig. 6 is an elevational front end view of my grinder machine.

Fig. 7 represents a transverse sectional view of a grinder head unit taken along 7—7 of Fig. 2, and Fig. 8 a partial longitudinal section taken along 8—8 of Fig. 7.

Fig. 9 shows a face view of a grinder head disc as seen from 9—9 of Fig. 2, and Fig. 10 a cross-sectional detail of tape backing means taken along 10—10 of Fig. 9.

Referring more specifically to the assembly Figs. 1, 2, and 6, my front and rear grinder ends may each be provided with a winch drum unit,

2

respectively comprising a pair of axially interspaced lower and upper sheaves designated 10A and 10B, also 11A and 11B. Such component winch sheaves or reels may be superimposed in the manner shown to combinedly stow a comparatively long batch of endless stock requiring relatively small floor space and of which substantially the entire strand length is exposed to air cooling.

Each reel or sheave of my duplex winches is purposely kept sufficiently large in diametral size that the spirally applied endless reelable strand 12 may not become harmfully stressed or abnormally set while repeatedly passing over the rim curvature. That is to say, each such reel diameter should be kept commensurate with the size of the reeled strand in order that the bending stress and its resulting elongation are not allowed to inordinately exceed the elastic limit of the reeled wire. It will be obvious that such appropriately sized reel may be used in combination with a single or multiple grinder head units at a proportionate difference in wire pass requirements for a stipulated diametral reduction of the treated work piece.

As detailed in Figs. 3 and 4, each such reel preferably utilizes a conventional cast double-arm spider 15 whose perimeter may be snugly embraced by a relatively thick hard wood rim 16 having a noncrowned face. Each end of such rim face may be reenforced against collapse under aggregate radial loading, by the affixed annular sheet metal side discs such as 17.

The cylindrical face of said rim may in close succession be provided with a series of sheet metal groove troughs such as 18 of which the next adjacent outturned legs 19 may be spot welded together to constitute a sheave. Each component trough may be individually rolled in arcuate segments with abutting ends welded at 23 to a sunken transverse keeper key 21. Several such keys may be equiangularly distributed about the rim axis and collectively fortify such assembly against tangential slip when subjected to heavy strand torque.

The cross-sectionally medial or bottom profile of each trough may be shaped to provide for a radially raised ledge 20 on which to track ribbon stock such as 12' (see Fig. 5A) or as an alternative, seat a pair of round wires such as 12 (see Fig. 5B). My endless work piece or treated strand 12 may be continuously and spirally wrapped about each pair of winch reels and then passed on to the other winch in the Fig. 1 manner.

Each such reel is arranged to keep its spirally laid wire in single level wound layer formation to permit of a fast drag transfer through my grinder without snarling or other entanglement. A like result may be attained by having the oncoming wire fall into spiral adjacency by the use of a plain tubular sheath without need of any reel grooves.

As will be seen from Fig. 2, each such sheave is purposely kept axially long in comparison to its diameter in order to accommodate numerous convolutions of stowed strand. My endless work piece may be trained between the mated sheaves of each winch in staggered American rope transmission fashion. Such or the equivalent spiral disposition serves to shift the reeled strand laterally and thereby cause it to travel from one toward the other winch end. The companion reel located at the opposite grinder end, is arranged to reverse such travel and bring the treated strand back into registry with the tubular grinder units 25A, 25B, etc. In substance, the novel unidirectional reeling principle underlying my grinder resides in spirally training the strand to peripherically embrace one of such winch reels while its mate is made to serve as conjoint control means that laterally shift the plural strand wrappings in a direction lengthwise of the axis of said one reel in a substantially maintained level wound status without need of reel reversal. Such duplex reeling system also affords an augmented batch stowage capacity, particularly for finer sized wires.

As represented in Fig. 1 by dotted lines, my endless work piece requires only two winch interconnecting strand components respectively designated 12A and 12B that travel in contrary directions along a closed circuit. The component 12A may be actively carried through one or more of said grinder units while the return strand component 12B may be laterally offset therefrom in registry with certain axially remote grooves of the companion sheaves 10B and 11B in a cleared relation to said grinder units as shown. If desired, the return component 12B may be equipped with a guided rider roller 13 that may be adjustably loaded for augmented sag by the weights 14.

Referring now to the mounting of my reels or sheaves, each winch preferably comprises a pair of vertical A-frames 26A and 26B that may be built up from structural steel and laterally reinforced by struts such as 27 (see Fig. 1). These frames may be erected upon a common sole plate comprising parallel channels such as 28 extending throughout the length of my grinder machine. Complementary stay beams such as 22 may interbrace the top regions of said frames against sway.

The upper and lower frame crossbars 29 and 30 may each reversely mount thereon a pillow block such as 31 which are preferably equipped with heavy duty needle roller bearings. Twin upper and lower reel mounting axles 32 and 33 are carried by mated sets of axially aligned pillow blocks. One such lower axle 33 may be rotatably driven by a unidirectional primary geared type of motor 34 mounted upon a lateral extension of the sole plate 28.

Because of the considerable drag exerted by multiple grinder heads, the fast running work piece 12 will be subject to a corresponding high tension. Such endless strand when trained about my mated winch reels as described, accumulatively imposes a considerable reaction on all pillow blocks. The use of the cited axle roller bearings materially mitigates the resulting friction losses.

After starting the motor 34, the tension of an operatively installed work piece in leaving the tandem grinder heads, will be considerably greater than its trailing tension. The provision for numerous closely spaced wire loops afford an adequate winch grip to drag a heavily loaded work piece without substantial drive slip. In normal operation, my dragged strand 12 is preferably run at a velocity of several thousand feet per minute to maintain intensive cutting action in cooperation with an abrasive agency that is slowly fed toward a localized grinding zone and whose grit may be completely spent in a single pass therethrough.

15 In order to adjustably control the work piece grip on the motor driven reel 10A and also to facilitate batch renewal, an upper sheave axle 32 may be retractably mounted by the use of a pair of guide levers such as 35 which may be fulcrumed at 36 to the upper crossbar 29 as shown. Each free lever end may be conjointly raised counterwise to strand tension by the dual hydraulic jacks 37A and 37B respectively equipped with a pump or equivalent fluid supply furnished from 20 a common ram controlled accumulator. These jacks may be manipulated in unison by the pump handle 38 which rocks the cross shaft 39 and thus maintains the upper and lower reel axles in substantial parallelism. The high pressure chambers of said jacks may be equalized by the pipe 25 40. An adjustable bleeder valve 41 limits the gross tension imposed on the winch wrapped work piece 12.

35 A lowering of the levers 35 simultaneously relieves strand tension in all reel interconnecting strands and thus materially increases the sag of the return component 12B, it being evident that a slight lever shift brings about a comparatively large multiplying slackening of such suspended strand. One or both of my duplex reel towers 40 may be equipped with such retractable levers. In so far as my jacks function as an inverted tackle block in raising the upper reel against prevailing multiple strand tension, this calls for a minor strand slip in successive looped reel coils. It is 45 therefore preferred to apply the ultimate jack effort while such installed endless strand is being given a certain degree of longitudinal movement.

Fig. 3 provides for supplementary roller means 42 mounted in bearings 43 between a pair of depending frame straps 44 and which means is arranged to bridge all strand loops that embrace mated reels such as 10A and 10B. Said roller 50 may be grooved in registry with the projecting trough legs 19 whereby to retain such threaded strands in place.

As regards my improved means for bodily replenishing a completed strand batch with dispatch, further reference is had to Fig. 1. After being slackened, a fully ground endless strand 60 may be severed at 45 and the respective cut ends carried to a demountable offtake drum 46 and to a cooperating batch supply spool 47 as schematically represented in dotted and dashed lines. Said drum is arranged to shift axially along a keyed supporting pin 46A and the spool is likewise arranged to shift along a keyless pin 47A. An auxiliary slow speed motor 48 may serve to intermittently rotate the drum 46 through its chain drive 49.

Batch replenishment may be further facilitated by the use of an interposed lead wire such as 24A or 24B of which a portion may finally be welded in place to renew a closed batch circuit.

75 In the event successive work piece batches should

coarse grit may at the termination of a strand treatment, be slowed down to enhance surface finish.

Referring again to Fig. 1, a coupling such as 82 may be installed between each rear end of the duplex shafts 63 and 64 and their gear interconnected motor 69. The opposite or forward end of such duplex shafts may be given a spline shape adapted to snugly engage a bridge strap 83 serving to block said shafts against rotation when the couplings 82 are disengaged. Alternate heads may then be swung in unison so as to interlockingly cause their respective tapes to lie in a common plane. Such stationary heads are utilized to treat ribbon stock in lieu of round stock.

A chain drive 84 interposed between the motor 69 and its coupling 82, may comprise a pinion sprocket carried by the shaft 63 and a larger sprocket 86 mounted about the differential gear casing 87 (see Figs. 1 and 2).

Such tubular casing may be coaxially mounted about the feed shaft 74 and encase a set of differential bevel gears 88 and 89, as indicated in dotted outline. The forward bevel gear 88 is affixed to said feed shaft while its opposed similar gear may be carried by a split feed shaft extension 90. The latter may be independently motor driven by a slow speed gyro reducer 91 through a train of change gears 92A and 92B. By virtue of the motorized Fig. 7 gearing and assuming the bridge strap 83 to be released, the feed shaft 74 may be brought to a rotative speed identical with that of the grinder heads 50A and 50B. Under such conditions, and while the gyro drive motor is cut out of service, the planetary gears 78A and 78B would not feed any tape toward their respective grinding zones. When however said change gears are gyro driven to impart a prescribed slow rate of rotation to the shaft extension 90, this will maintain a corresponding feed for all head tapes. The use of a suitable change gear ratio provides for a faster tape feed for large than for small wire sizes.

When treating ribbon stock, the described disengagement of the couplings 82 will still allow the tapes to be advanced collectively, although the locked grinder heads remain stationary. For ribbon stock, it is desirable to reversely feed such tapes in alternate head units from opposed edges toward the center line of the treated ribbon stock. Such disposition prevents formation of pronounced crowning of its treated flat side faces. When only one ribbon face is to be abraded, superimposed thin strands 42' (see Fig. 5A) may be simultaneously dragged through multiple grinder head units.

Such unidirectional endless strand treatment affords an advantage over intermittently reversed strands of finite length in that the allowable pass velocity may be faster and does not suffer a loss of productive capacity during frequent reversal periods.

My machine is particularly adapted to treat reelable alloy wires of reasonably large size and may economically impart a five percent weight reduction thereto sufficient to grind out exposed crevices, eliminate decarbonization and otherwise perfect its surface for a subsequent redraw into a smaller wire size. As applied to plow steel cables for long suspension bridges, the resulting increase in mean tensile strength reduces its associated own weight sag.

The foregoing rather explicit structural disclosure and its functional behavior will it is believed, make evident to those skilled in this art,

the more outstanding commercial and operative advantages afforded by my grinder improvements, and I reserve the right to equivalently modify such illustrated design features, all without departing from the spirit and scope of my invention, heretofore described and more particularly characterized in the appended claims.

I claim:

1. A strand grinder machine comprising a pair of winch units respectively including mated frames that each mount twin axles thereacross and which axles respectively carry a reel adapted to have an endless reelable work piece trained about both such winch units with a single active and a single return work piece component transversely suspended between said units, tubular grinder means interposed between said winch units and which active component is operatively conveyed through said grinder means, and a unidirectional motor connected to drive one of such axles to advance the work piece longitudinally.
2. A strand grinder machine comprising a pair of winch units respectively including parallelly mounted axles that each carry a reel adapted to have an endless reelable work piece threaded about both such winch units with a single active and a single return work piece component transversely suspended between said units, tubular grinder means interposed between said winch units and which active component is cooperatively conveyed through said grinder means, means for adjustably altering the axle spacing of one such winch unit, and motorized means driving one of the axles to advance the work piece longitudinally.
3. A strand grinder machine comprising a winch drum unit including mated frames respectively provided with a crossbar, retractile guide means for each crossbar, a pillow block upheld by each such guide means to lie in axial registry, an axle spanning said pillow blocks, a reel mounted on said axle as a strand carrier, grinder means operatively engaging the work piece, and actuating means for simultaneously shifting said guide means whereby to adjustably alter the axial position of said reel.
4. A strand treating grinder machine adapted to treat a reelable work piece and which machine comprises a winch unit including mated frames, retractile guide means for each frame, a pillow block supported by each such guide means, an axle spanning said pillow blocks, a reel mounted on said axle as a strand carrier, actuating means for shifting said guide means whereby to adjustably slacken the carried strand, grinder means operatively engaging the work piece, and supplementary roller means serving to retain such slackened strand in running registry with the reel perimeter.
5. A strand treating grinder machine comprising a winch unit provided with axially spaced complementary reel drums adapted to have an endless reelable work piece looped about both such drums, grinder means actively cooperating with said work piece, a series of strand receiving endless troughs superimposed upon and laterally distributed in succession around the peripheral rim surface of one such drum, said troughs each being cross-sectionally shaped to provide for opposed outstanding legs and a radially raised ledge interposed between said legs, and means securing such troughs to said rim surface.
6. A strand treating grinder comprising a pair of winch units respectively provided with mated

vary materially in overall finite length, such incorporated welded lead wire may be correspondingly altered to maintain a fixed loop length.

The geared auxiliary motor 48 may replenish a finished batch at a linear drag velocity substantially slower than the normal travel rate prevailing during a strand grinding period. The armature of the primary motor 34 may be clutch equipped but may also be idly rotated when the motor 48 is made operative. In such event, a completed severed batch will be bodily withdrawn from the duplex reels and a new batch coming off the supply spool 47 will be simultaneously dragged in its place for welding into a closed endless circuit. By now actuating the handle 38, the jacks may be manipulated to restore a suitable initial tension to a newly installed work piece batch. While being severed or spliced, the slackened strand ends may be retained against undue separation by the complementary frame mounted clamps 51A and 51B.

The fact that the offtake drum 46 removes a completed batch at the same time that a new batch is being fed off the supply spool 47, cuts down the required replenishing time and aids in maintaining a high productive capacity for my grinder without prolonged shut down between active grinding periods.

The axial length of each reel is preferably kept sufficiently wide to stow a comparatively long length of smaller sized wire or ribbon stock. For such a condition, substantially all of the provided reel width may be selectively utilized and thus provide convenient means for accommodating different endless batch lengths. Minor variations in mill run lengths may be compensated by the cited incorporation of a lead wire. Fig. 2 shows the offtake drum 46 and batch supply spool 47 positioned in alignment with a fully filled winch reel. Such drum and spool may however be shiftably retained in registry with an intermediate wire loop position. If desired, my batch replenishing spool may also be elevated and upheld across complementary frame stay beams such as 22.

Fig. 8 is illustrative of a preferred grinder unit and as such may comprise a pair of flanged rotary or stationary head discs 50A and 50B that are overhangingly affixed to opposite ends of the tubular spindle 52. Said spindle may rotate in a pair of ball bearings shown as individually mounted in the pedestals 54 and 55 that are interspaced to install the spindle drive gear 56 therebetween. A meshing idler gear 57 may be mounted upon a pedestal bridge pin 58 as shown. Each such pedestal may be separately supported upon a superstructure comprising the rolled tie or cross beam 59 whose ends are affixedly carried by a pair of parallel rolled stringer beams 60A and 60B of substantial web depth that extend crosswise beneath the head discs. Said superstructure may be upheld by a plurality of structural uprights 61A, 61B, etc. (see Figs. 1 and 2) erected upon the sole plate 28. While only two grinder units are disclosed, a heavy duty machine may consist of more units than are shown. The rate of grinder output may be increased in a proportionate relation to the number of grinder heads employed, provided their combined abrasive drag is kept within bounds.

For reasons that will appear presently, in the treatment of ribbon stock 12' (see Fig. 5A) the rotatably mounted discs 50A and 50B are all held

stationary. For wire stock 12 (see Fig. 5B), it is preferred to rotate successive head pairs in reverse directions since such handling maintains a substantially balanced torque on treated wire.

To this end, dual disc drive shafts 63 and 64 may run in hanger bearings such as 65 suspended from appropriate tie beams 59 as indicated in Figs. 7 and 8. Corresponding ends of such dual shafts may be inter-connected to run in reverse directions by the spur gears 66 and 67. A stringer supported cradle 68 may demountably support a slow speed supplementary motor 69 (shown in dotted and dashed outline in Fig. 7) which may coaxially align with and be directly connected to one dual shaft such as 63. Each of said shafts may carry a plurality of driven staggered gears such as 70 (see Fig. 8) that alternately mesh with the radially offset idler spindle gears 57 and 57'. This disposition allows certain alternate head units to be reversely driven by the duplex shafts 63 and 64 in the direction indicated by arrows in Fig. 1. Such refinement obviates an accumulative twist being imposed on a long treated wire by a heavy abrasive torsional drag.

Attached to one stringer beam as 60A, is a series of sectionalized brackets such as 73 which longitudinally mount the single tape feed shaft 74. Said shaft carries a tape feed gear 75 adjacent to the respective opposed bracket ends. Each bracket may be further provided with a fork extension for mounting the idler feed gear 76 that meshes with its driven feed gear 75. The previously cited pedestal journals 53 may each uphold a twin master gear 77 of which the inner component meshes with a registering idler feed gear 76. The gear arrangement is such that the master gear may rotate independently of the spindle 52. The other of said twin master gears 77 may mesh with a pair of planetary head gears 78A and 78B.

The outturned cup rims of my abrasive head discs are interspaced to leave ample serving room between next adjacent head units. Each head disc provides for the symmetrically disposed dual tapes 79A and 79B (see Fig. 9) which are individually advanced over suitable guide rollers between opposed spring-backed jaws of the pivoted type such as 80 and into abrasive engagement with the endless strand 12 that may be loosely threaded through the tandem spindles 52.

Said tapes are respectively arranged to feed from the radially opposed supply spools 85A and 85B and led to one of the continuously driven feed rollers 81A or 81B. The respective roller shanks may be journaled through separate head disc bores to overhangingly mount a planetary gear thereon such as 78A or 78B of which the diameter may be kept identical with their meshing common master gear 77. The resulting gear train advances the abrasive tapes of each disc in opposed directions as indicated. When slowly fed, the grit of each tape becomes substantially spent in a single pass through its localized cutting zone. For a given head rotation, the direction of advance of the complementary tapes may be reversed by a shift in the position of the feed rollers.

The resulting lengthwise work piece stroking with partially loaded tape, attains a substantially smooth, bright finish although fast cutting 20 mesh grit may be employed. Such processing in turn, permits of intensively grinding a long length of strand stock on a rapid, low cost basis. Where a still higher grade of finish is sought, finer tape grit may be resorted to or the feed rate of loaded

reels adapted to install a reelable work piece about such winch units and which work piece includes a component transferrably suspended between said units, a primary motor normally driving a reel of one such unit and serving to impart longitudinal grinding movement to the installed work piece for a restricted period, grinder means operatively engaging said suspended component, an offtake drum and a batch supply spool interposed between said winch units, and an auxiliary motive agency for driving said drum and serving in an intervening period to simultaneously rotate the armature of the primary motor at a slower than its normal grinding speed.

7. A grinder machine comprising twin reel means axially interspaced and adapted to have a reelable strand portion transferrably suspended therebetween, a superstructure including substantially parallel stringer beams interposed between the perimeters of the reel means, plural grinder units respectively including a rotatable head arranged to abrasively treat said strand portion with abrasive tape and which units are disposed in tandem lengthwise of said beams, reversely rotated duplex drive shafts extending beneath said units and respectively serving to rotate the head of alternate grinder units, and a single tape feed shaft bracketed exteriorly to one such beam and actuated to run in unison with a certain duplex shaft.

8. A strand treating grinder machine comprising a pair of winch units spaced apart at a fixed distance and respectively provided with mated reels adapted to install thereon a reelable endless work piece of finite circuitous extent including a work piece component transferrably suspended between said units and the stock batch for which work piece is furnished in different mill run lengths, grinder means operatively engaging said suspended work piece component, and means including an accessory driven offtake drum and a cooperating batch supply spool aiding to incorporate a lead length into the aforesaid circuit and thereby compensate for discrepancies in successive mill run lengths.

9. A strand treating grinder machine comprising a pair of axially spaced reel means adapted to abrasively treat a relatively long reelable endless work piece that perimetricaly embraces both such means to stow a major batch length portion thereon and having relatively short dual strand portions respectively suspended in substantial parallelism between corresponding axial end regions of said pair of reel means, grinder means operatively engaging one such strand, drive means for rotating one of said reel means and advancing the dual strand portions in opposite travel directions, and means for laterally shifting the work piece out of alignment with respect to said one strand toward its opposed reel end region and for reversing such shift when arriving at the other reel means whereby a component of said endless batch is brought back into substantial alignment with said one strand for delivery toward said grinder means and which reel means except for said strands constitute the primary means for stowing said batch thereon.

10. A strand treating grinder machine comprising a pair of axially spaced reel means adapted to abrasively treat a relatively long reelable endless work piece that perimetricaly embraces both such means to stow a major batch length portion thereon and having relatively short dual strand portions respectively suspended between said pair

of reel means, tubular grinder means operatively engaging one such strand and which strand is entered through the grinder means, drive means unidirectionally rotating one of said reels, and means for spirally shifting said reel embracing work piece in a direction lengthwise of each reel axis and which shift directions are reversed on the respective reel means to effect a one-way approach toward the grinder means during successive passes of said endless work piece through the last named means.

11. A strand treating grinder machine comprising a pair of winch units respectively provided with complementary reels adapted to install endless work pieces of divers lengths when successively looped about such units with an active work piece component and a single return component that are transferably suspended between such units in laterally interspaced relation contingent upon the number of loops required to service the respective work piece lengths, grinder means operatively engaging said active component, and a driven offtake drum and a cooperating batch supply spool of which one such is rendered axially shiftable to accommodate a change in the interspacing between said active and return components.

12. A strand treating grinder machine comprising a pair of reeling units respectively comprising an axle mounted reel which are respectively interspaced in substantial parallelism and mutually adapted to longitudinally drag a relatively long endless strand as a work piece throughout the length thereof in successive passes, said strand being trained to perimetricaly embrace said reels spirally in level wound layer formation to leave relatively short dual strand portions respectively suspended between said reeling units, grinder means operatively engaging one such dual strand portion, drive means unidirectionally advancing the dual strand portions in opposite travel directions, means associated with said reeling units for laterally shifting the strand portion that perimetricaly embraces one reel in a direction axially of such reel in a substantially maintained level wound status, retractable guide means applied to a reeling unit, and releasable actuating means for the guide means serving to adjustably tension the strand.

13. A strand treating grinder machine comprising a pair of reeling units respectively comprising an axle mounted reel which are respectively interspaced in substantial parallelism and mutually adapted to longitudinally drag a relatively long endless strand as a work piece throughout the length thereof in successive passes, said strand being trained to perimetricaly embrace said reels spirally in level wound layer formation to leave relatively short dual strand portions respectively suspended between said reeling units, grinder means operatively engaging one such dual strand portion, drive means unidirectionally advancing the dual strand portions in opposite travel directions, means associated with said reeling units for laterally shifting the strand portion that perimetricaly embraces one reel in a direction axially of such reel in a substantially maintained level wound status, retractable guide means applied to the respective ends of a reel axle, and hydraulic means simultaneously actuating each such guide means to an equalized extent.

14. A strand treating grinder machine comprising a pair of reeling units respectively comprising an axle mounted reel which are respectively

interspaced in substantial parallelism and mutually adapted to longitudinally drag a relatively long endless strand as a work piece throughout the length thereof in successive passes, said strand being trained to perimetricaly embrace said reels spirally in level wound layer formation to leave relatively short dual strand portions respectively suspended between said reeling units, grinder means operatively engaging one such dual strand portion, drive means unidirectionally advancing the dual strand portions in opposite travel directions, and means associated with said reeling units for laterally shifting the strand portion that perimetricaly embraces one reel in a direction axially of such reel in a substantially maintained level wound status.

15. A strand treating grinder machine comprising a pair of winch reels mutually adapted to longitudinally drag an endless strand as a work piece in successive passes, said strand being trained to repeatedly loop said reels in level layer formation, an axle supporting one of said reels intermediate its axle end regions, an antifriction

5
10

rolling type of bearing serving to uphold each such axle end, grinder means operatively associated with said strand and imposing a substantial tension lengthwise of the strand portion looped about said reels, unidirectional motive means provided with a speed reducer coupled to one end of said axle, and supplementary substantially duplicate winch reels except for the applied motive means serving to laterally return the strand back into registry with the first oncoming loop of the initially named pair of winch reels.
